INVENTOR
WILLIAM H. BETTS
By *Edward F. Langans*
ATTY.

UNITED STATES PATENT OFFICE.

WILLIAM H. BETTS, OF ST. LOUIS, MISSOURI.

SOLE PROTECTOR.

1,418,425.

Specification of Letters Patent. Patented June 6, 1922.

Application filed January 14, 1921. Serial No. 437,196.

To all whom it may concern:

Be it known that I, WILLIAM H. BETTS, a citizen of the United States, and resident of the city of St. Louis and State of Missouri, have invented certain new and useful Improvements in Sole Protectors, of which the following is a specification containing, a full, clear, and exact description, reference being had to the accompanying 10 drawings, forming a part hereof.

My invention relates to improvements in sole protectors and has for its primary object the construction of a protector which may be driven into the sole or other part 15 of the shoe and it will automatically clinch within the material and will not pass through the sole and not require any subsequent clinching.

This invention is an improvement on 20 the sole protector previously patented by me on July 15, 1920, Patent No. 1310050.

In the drawings:

Fig. 1 is an enlarged side elevation of my protector.

25 Fig. 2 is a sectional elevation of the same showing the same applied to the sole of the shoe, a portion of the shoe sole being broken away.

Fig. 3 is a bottom plan view of the same.

30 Fig. 4 is a top plan view of the same.

Referring to the drawings, 5 is a combined driving head and wearing plate, which is substantially elliptical and provided with prongs 6 formed at substantially right angles with the head 5. The prongs 6 are arranged at each end of the driving head 5 and are provided with outer curved faces 7 and with inner straight plain faces 8; the outer curved faces and the inner straight 35 faces merging together and forming points 9. The side edges of the prongs are plain faces merging together and forming 40 points 9. The side edges of the prongs are parallel and the prongs are of uniform width from the head or wearing plate to the points.

45 It will be observed from the drawings that the outer faces of the prongs are struck on circles of different radii and might be termed prongs whose outer faces are composed of composite surfaces. The curved 50 outer surface on each prong adjacent the wear plate is formed on a circle of a smaller radius than the curved surface adjacent the prong ends. By forming the outer face of the upper portion of the prong on a smaller 55 radius as stated, the thickness of the prong in this portion is reduced, thus lessening

the resistance offered in seating the protector in the leather. The leather, which is compressed by the entering prong, thus expands behind the thickened middle portion of the prong tightly gripping the latter and forming a close joint on the exterior surface of the prong. It will also be observed that the prongs are bent with sharp inner angles relative to the head or wearing 60 plate, and that the thickness of the prongs at this point, which may be designated as at 10, is less than the material out of which the protector is formed and hence less than the thickness of the wear plate or of the portion of the prong just beyond the neck 10. This assists in the easy bending or clinching of the prong. This relatively thin portion is purposely designed in making the 70 protector and arises from making a sharp angle as at 11 on the inside faces of the prongs and rounding the outer surfaces of the prongs adjacent the driving head or wearing plate.

Having fully described my invention, 75 what I claim is:

1. A sole protector comprising a driving head and wear plate having a prong formed integral with each end thereof, said prongs extending with sharp inside angles from 85 the plate and having plane, smooth, straight inner faces and the outer faces of said prongs composed of composite curved surfaces, said prongs being of slightly less thickness at their corners than at a distance 90 from the corners.

2. A sole protector comprising a driving head and wear plate having a prong formed integral with each end thereof, said prongs being arranged with sharp inside angles to 95 the plate and having smooth, straight, inner surfaces and outer composite curved surfaces, the surface adjacent the point of the prongs being struck from an arc of a circle whose radius is greater than the surface adjacent the plate, the formation of said sharp angle and curved surface adjacent the plate reducing the thickness of the prong at the point of its connection with the plate below that of the plate or the 100 prong beyond the said reduced point of connection whereby the inward clinching of the prongs is facilitated.

In testimony whereof, I have signed my name to this specification.

WILLIAM H. BETTS.
